UNITED STATES PATENT OFFICE

JOHN T. DE VEAU AND HERBERT MALLET, OF GREENPORT, NEW YORK

SHIP GANGWAY

Application filed March 27, 1930. Serial No. 439,462.

This invention relates to ships' gangways and particularly to those gangways which are pivoted at the side of the ship.

Ships which are intended to lie at anchor and be served with small boats are usually provided with one or more gangways which are pivoted from a platform which may or may not be removed or swung into a vertical position. Usually the platform is provided with a rail and the gangway is also provided with a rail.

In the past, it has been the usual custom to make the railing of the platform and the railing of the gangway independent of each other. This necessitates a flexible connection between the two railings which destroys a continuity between the two. When the gangway is raised prior to getting the ship under way, then the space between the two railings is closed and the platform railing is naturally at a greater distance from the platform, than the gangway rail is above the gangway.

The primary object of this invention is the provision of an improved railing for a pivoted ship's gangway wherein the railings of the upper platform and gangway are always continuous whether the gangway is lowered or raised and wherein the gangway will always be held firmly in place.

Another object of the invention is the provision of an improved railing with stanchions having flanged pivots for their support.

Other and further objects of the invention will appear to those skilled in the art from a reading of the complete specification and claims.

Referring to the drawings wherein is illustrated a preferred embodiment of the invention.

Figure 1 is a side view of a ship with the gangway lowered.

Figure 2 is a similar view with the gangway raised.

Figure 3 is an enlarged view of the flanged pivot and its mountings.

Figure 4 is a cross section on the line 4-4 of Figure 3.

Figure 5 is a similar cross section, but with the pivot unsectioned.

The same reference numerals are used for

the same or similar parts throughout the drawings and specifications.

The numeral 10 designates the ship with a deck level at 11 and having an upper gangway platform 12. This platform is usually secured in place by eyes and detachable braces 13.

Secured to the platform 12 are the removable upright stanchions 14 which support, at their upper ends, the rail 15. To the after edge of the platform 12 is pivoted, at 16, the gangway having the sides 17 and the lower landing 18 which may be integral with the sides 17. The gangway may be supported by any suitable means as the bail member 19 which in turn is supported from a block and fall 20.

Pivoted at the end of the platform railing 15 is a gangway railing 21 which is of a length substantially equal to the length of the step supporting sides 17.

The particular feature of my invention is the connection between the step-supporting sides 17 and the gangway railing 21. Connected to the gangway railing 21 at its lower side, will be found one or more swinging stanchions 22. While it would be an easy matter to pivot the lower ends of the stanchions 22 to the gangway sides 17, such a pivot must, to meet all conditions be strong enough to withstand the strains of usage, must move freely and must not protrude far on either side of the relatively thin gangway sides 17.

To accomplish these ends, I have provided such a pivot construction which is so constructed that it may lie wholly on the outside of the gangway sides 17 and yet will not protrude much beyond the outside of the stanchions and none beyond the railing.

Referring particularly to Figures 3, 4 and 5, a plate 23 which I have shown in this embodiment as being circular, is provided with a circular opening in which is located the pivot member 24.

The plate 23 is provided on its rear with two progressively undercut portions 25, 26.

Intermediate the axial length of the pivot member 24 is a flange member 27 which in the form shown, extends circumferentially and

is of a shape to fit in the undercut 25. A securing plate 28, of annular shape fits at its outer edge the under cut opening 26 and at its inner edge has contact and bearing with the main body of the pivot member 24. The inner end of the pivot member 24 is so placed with relation to the rear face of the securing plate 28 and the edge 29 of the plate 23 that the pivot may be freely turned without binding. The flange 27 is held between the plate 23 and the securing plate 28 by suitable securing means as the screws 30.

On the outer end of the pivot member 24 is a lug 31 containing a socket 32. Secured, as by threads or by brazing, or both, in the socket 32 is the stanchion 22, already described.

The pivots 22^a and 15^a at the upper ends of the stanchions 22 and between the railings 15 and 21, are parallel with the axes of the pivot members 24 and consequently when the gangway is raised toward the position shown in Figure 2, the parallel relation between the railing 21 and the gangway side 17 and also between the stanchions 22, will be maintained.

The extension of the flanges 27 over such a wide circumference and over such a large surface, renders the device very stable and not subject to binding or dislocation when in use. The large circumference of the flange 27 gives the device great strength in all directions while not interfering with the movement in its plane of rotation.

While there is illustrated and described in detail an embodiment of the invention, it is desired to have it understood that the invention is not limited to the exact showing and that modifications and changes may be made without departing from the spirit of the invention and within the scope of the appended claims.

Having described this invention what is claimed and desired to secure by Letters Patent is:—

1. In a ship's gangway having a platform and platform railing with gangway sides pivoted to the platform and a railing pivoted to the platform railing, a stanchion pivoted at its upper end to the gangway railing, a pivot at its lower end, a plate having an opening at its forward side and a depression at its rear, the opening being of a size to fit the stanchion pivot, the pivot having a flange to fit the depression.

2. In a ship's gangway having a platform and platform railing with gangway sides pivoted to the platform and a railing pivoted to the platform railing, a stanchion pivoted at its upper end to the gangway railing, a pivot at its lower end, the pivot having a flange intermediate the ends of its bearing surface, a plate having a bearing surface adjacent its face and a depression at its rear to

receive the flange and a securing plate to hold the pivot in place.

3. In a ship's gangway having a platform and platform railing with gangway sides pivoted to the platform and a railing pivoted to the platform railing, a stanchion pivoted at its upper end to the gangway railing, a pivot at its lower end, the pivot having a flange intermediate the ends of its bearing surface, a plate having a bearing surface, adjacent its face and a depression at its rear to receive the flange and a securing plate to hold the pivot in place, the securing plate having an opening to provide a bearing for a portion of the pivot.

In testimony whereof we hereunto affix our signatures.

JOHN T. DE VEAU.
HERBERT MALLET.
